UNITED STATES PATENT OFFICE.

FRITZ FINCKH, OF ESSEN, GERMANY, ASSIGNOR TO FRIED. KRUPP AKTIENGESELLSCHAFT, OF ESSEN-ON-THE-RUHR, GERMANY.

BARREL-RECOIL GUN.

1,379,543.

Specification of Letters Patent. Patented May 24, 1921.

Application filed September 4, 1920. Serial No. 408,376.

To all whom it may concern:

Be it known that I, FRITZ FINCKH, residing at Essen, Germany, a citizen of the German Republic, have invented a certain 5 new and useful Improvement in Barrel-Recoil Guns, of which the following is a specification.

This invention relates to barrel recoil guns and the object of the invention is to enable the gun barrels of naval and railway guns, which are to be made, or already existant naval guns to be used both on a naval carriage or a railway carriage without important alterations being made in the gun 15 barrels and cradles.

The invention will be described with reference to the accompanying drawings in which—

Figure 1 is a side elevation of a barrel 20 recoil gun showing the parts pertaining to the present invention.

Fig. 2 is the corresponding left hand end view and

Fig. 3 the corresponding plan view.

25 Figs. 4 to 6 are views corresponding to Figs. 1 to 3 of a second construction.

Figs. 7 to 9 are similar views of a further construction usual hitherto and

Fig. 10 is a side elevation, partly in section, of the gun barrel of Figs. 7 to 9 but altered according to the invention.

Fig. 11 is a section on the line 11—11 of Fig. 10, looking from the left, and

Fig. 12 is the corresponding plan view to 35 Fig. 10.

The arrangement shown in Figs. 1 to 3 will be described first.

The gun barrel A is carried by a cradle B, which cradle carries two pairs of trunnions (E, E¹), the geometrical axis of which trunnions E passes either through the center of gravity of the parts of the gun which are swung when the elevation is made or lies in the vicinity of this center of gravity, 45 while the trunnions E¹ lie very near the breech end of the gun barrel.

If the parts described are to be used for a naval gun, the trunnions E are laid in the bearings provided on the gun carriage. If, 50 on the other hand, the parts illustrated are to be used for a railway gun carriage, they are carried by means of the trunnions E¹ in the railway gun carriage frame. The parts which oscillate about the axis of the

trunnions are then considerably preponderant in weight at the front, which preponderance of weight has to be compensated by an equalizer, but no provision need be made for the parts lying behind the trunnions, particularly the recoiling gun barrel, as for 55 instance by preparing a pit between the rails or by an arrangement for enabling the trunnion bearings of the carriage confined to the profile of the railway loading gages to be transferred from the transport position 60 into a higher firing position.

The construction shown in Figs. 4 to 6 differs only from that described, in that the cradle F is provided with an arrangement for enabling a pair of trunnions (G) to be 70 detachably fixed in either of two different positions of the cradle. For this purpose the cradle has two pairs of oppositely located flat surfaces (f¹, f²) on which plates g¹, which are in one piece with the trunnions G, are to be affixed by screws. The plates g¹ carry disk shaped members g², intended to fit into circular recesses f³ (see Fig. 4) in the body of the cradle and thereby take the pressure off from the attachment screws. If the parts illustrated are to be used on a naval gun carriage, the trunnions G are attached to the front flat faces (f¹) of the cradle, whereas when the parts are used on a railway gun carriage the trunnions are to be screwed to the rear flat faces (f²).

The cradle H shown in Figs. 7 to 12 carries a pair of trunnions J, which is mounted on one end of the cradle. The cradle H 90 also carries a member h¹, in which the cylinder K of a recoil brake and a running out gear is attached in an easily detachable manner. The corresponding piston rod k¹ can be attached to a horn m¹ on a ring M 95 rigidly attached to the gun barrel. On the member h¹ an eye h² is mounted for a purpose to be hereinafter described.

When the cradle H together with the gun barrel, brake, and the like is used for a naval gun, these parts are put together in the manner shown in Figs. 7 to 9. The trunnions J then lie at the end of the cradle which is next to the muzzle of the gun barrel, and the elevating gear is attached to the eye h². If 105 on the other hand the arrangement shown in Figs. 7 to 9 is to be built into a railway gun carriage, the cradle H is inserted in the

frame of the gun carriage in a reversed position (see Figs. 10 and 12).

The end of the cradle which carries the trunnions J is then located in the vicinity of 5 the breach of the gun barrel. In this case the easily detachable cylinder K, which is connected to the member h^1 of the cradle H, must also be reversed, so that the end of the cylinder which is provided with a stuffing 10 box for the rod k^1 is turned toward the horn m^1 of the ring M.

Furthermore the rod k^1 is lengthened by a piece k^2 screwed to it and attached to the horn m^1 . When the cradle H is used on a 15 railway gun carriage, the ring M may bear against the cradle H when the gun is in the firing position, or if the distance of the trunnions J from the breach end of the gun barrel is to be increased and the preponderant 20 weight in front of the parts oscillating about the trunnions is to be reduced, a ring N may be inserted between the rear end of the cradle H and the ring M and be attached to the cradle. The ring N is provided with a pro- 25 jection n^1 which carries an eye n^2 for the attachment of the elevating gear and has a boring n^3 for the rods k^1 , k^2 . The last described arrangement is specially suited for the conversion of existing naval guns.

30 The ring N may also be used in the constructions shown in Figs. 1 to 6. In this case the piston rod of the recoil brake of the running out gear must naturally also be lengthened.

35 Claims.

1. A barrel recoil gun which comprises a gun barrel, a cradle, and means on said cradle whereby the horizontal axis about which the gun barrel oscillates can be

brought to distances of different length 40 from the breech end of the cradle.

2. A barrel recoil gun which comprises a gun barrel, a cradle, means carried by said cradle to enable the gun barrel to be supported on horizontal axes at distances of dif- 45 ferent lengths from the breech end of the gun barrel, a recoil brake and run-out gear carried by said cradle and extensible means for connecting the recoil device to the gun barrel. 50

3. A barrel recoil gun which comprises a gun barrel, a cradle therefor, two pairs of trunnions carried by said cradle whereby the horizontal axis about which the gun barrel oscillates may be brought to different dis- 55 tances from the breech end of the gun barrel.

4. A barrel recoil gun which comprises a gun barrel, a cradle therefor, trunnions carried by said cradle, said trunnions being arranged so that the horizontal axis about 60 which the gun barrel oscillates may be brought to different distances from the breech end of the cradle.

5. A barrel recoil gun which comprises a gun barrel, a cradle therefor, two pair of 65 trunnions rigidly carried by said cradle, said pairs of trunnions being spaced longitudinally on said cradle, whereby the horizontal axis about which the gun barrel oscillates may be brought to different distances from 70 the breech end of the gun barrel.

The foregoing specification signed at Essen, Germany, this 18th day of May, 1920.

FRITZ FINCKH.

In presence of—

HANS GOTTMANN,
JOSEF OLBERTZ.
